(57) **CLAIM**

The ornamental design for a steel tongue drum, as shown and described.

DESCRIPTION

FIG. 1 is a front, right and bottom perspective view of a steel tongue drum showing my new design;
FIG. 2 is a rear, left and top perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of area 9 in FIG. 1; and,
FIG. 10 is an enlarged view of area 10 in FIG. 5.
The broken lines in the figures illustrate portions of the steel tongue drum that form no part of the claimed design.
The dash-dot-dash broken lines show the boundaries of the enlarged views and form no part of the claim thereof.
